UNITED STATES PATENT OFFICE

2,090,329

CUTTER CHAIN

Robert K. Jeffrey, Bexley, Ohio, assignor to The Jeffrey Manufacturing Company, a corporation of Ohio

Original application January 3, 1936, Serial No. 57,359. Divided and this application November 28, 1936, Serial No. 113,172

7 Claims. (Cl. 262—33)

This invention relates to a cutter chain of the type employed with a kerf-cutting mining machine.

An object of the invention is to provide a cutter chain of minimum weight, and one which can be readily disconnected and connected together with a few common tools.

Another object of the invention is to provide a "stiff back" type of cutter chain which provides a ready escape for any particles of coal caught in the chain links.

Another object of the invention is to provide a very strong cutter chain which, however, is easily disassembled in the field.

Other objects of the invention will appear hereinafter, the novel features and combination being set forth in the appended claims.

In the accompanying drawing,

Fig. 1 is a side elevational view of a portion of a cutter chain comprising my invention;

Fig. 2 is an enlarged side elevational view of a bit carrying link of my improved cutter chain;

Fig. 3 is a plan view of the link of Fig. 2;

Fig. 4 is a partial transverse sectional view taken on the line 4—4 of Fig. 2, looking in the direction of the arrows;

Fig. 5 is a side elevational view of the connecting link of the chain of Fig. 1;

Fig. 6 is a perspective view of the coupling pin of the chain of Fig. 1;

Fig. 7 is an enlarged sectional plan view of a detail showing the coupling pin and its manner of coupling a bit carrying link and a connecting link and taken on the line 7—7 of Fig. 1, looking in the direction of the arrows; and

Fig. 8 is a perspective view of a coupling pin retaining key.

As seen in Fig. 1 of the drawing, the cutter chain 10 comprises alternate inter-connected bit carrying links 11 and connecting links 12. The bit carrying links 11 and connecting links 12 are preferably so formed that the cutter chain 10 is of the "stiff back" type. That is, the chain can be bent into a concave curve but not into a convex curve. The construction of the bit carrying links 11 is best seen in Figs. 2, 3 and 4 of the drawing, to which attention is now directed.

The bit carrying links 11 are preferably cast of steel and comprise a pair of spaced parallel side walls 13, 14. Adjacent their bottoms said side walls 13 and 14 carry laterally extending gibs 15, 16 which are each adapted to ride in a recess in the guideway of a cutter bar to retain the cutter chain 10 on said cutter bar. The bottom portions of said gibs 15, 16 are arcuate, as

seen at 17, to provide an extensive bearing area between the curved outer end of the cutter bar and the chain, thereby reducing wear on each, and stabilizing said cutter chain.

Intermediate the longitudinal ends of the side walls 13, 14 and extending across the tops thereof and integrally attached thereto, there is provided an upwardly extending bit carrying post or lug 18, the axis of which forms an angle with the plane of the side walls 13, 14, as illustrated in Fig. 4. This angle will vary for the different bit carrying links 11, whereby the angle which the cutter bit 19, which is carried by said post or lug 18, makes with the plane of said side walls 13, 14 varies with the different links of the cutter chain. This, of course, provides for the cutting of a kerf which is wider than the thickness of the cutter bar, in a manner well understood in this art.

The lug 18 is apertured at 20 to receive the cutter bit 19 which may be held in said aperture 20 with its cutting point extending in either direction, whereby the cutter chain may travel in either direction to perform cutting operations. A pair of studs or set screws 21', 21' are screw-threaded into the lug 18 at opposite sides of the aperture 20 to lock the cutter bit in adjusted position.

Adjacent the tops of the side walls 13, 14 and at each end thereof there is provided a laterally extending wing, wings 21, 21 being attached to the side wall 13 and wings 22, 22 being attached to the side wall 14. These wings 21, 21 and 22, 22 are provided with bottom bearing surfaces 23, 23 and 24, 24, respectively, which are adapted to ride upon the outer edge of the cutter bar to transmit any thrust received by the bit carrying links 11 to said cutter bar. In general, the cutter bar will be provided with a wear strip upon which said bearing surfaces 23, 23 and 24, 24 are adapted to bear.

Also attached to the tops of the side walls 13, 14, adjacent each end thereof but projecting inwardly of said side walls, are additional wings, wings 25, 25 being attached to wall 13 and wings 26, 26 being attached to wall 14. These wings 25, 25 and 26, 26 are provided on their lower faces with bearing surfaces 27, 27 and 28, 28 which co-operate with the connecting links 12 to provide the "stiff back" feature of the cutter chain 10. This will be described more in detail hereinafter.

It is to be particularly noted that the wings 21, 21 and 22, 22 are longitudinally spaced apart, thereby providing an open area between them which will allow for free escape of any coal which may be caught between the bearing surfaces 23,

23 or 24, 24 and the cutter bar. This also provides for ready travel of the bit carrying links around the arcuate portion of the cutter bar, during which travel the bearing surfaces 23, 23 5 and 24, 24 do not contact the cutter bar, but the curved portions 17 of the gibs 15 and 16 provide bearing surfaces therebetween.

It is also to be noted that the wings 25, 25 and 26, 26 have their contiguous ends spaced 10 apart transversely and are also spaced from the lug 18, thereby providing an open-topped bit carrying link 11 which will allow for the free escape of any material which may be caught between the link and the cutter bar or may be 15 caught between a tooth of the drive sprocket chain and the bit carrying link 11.

To provide further ready release of any material which may be caught between a drive sprocket chain tooth and the bit carrying link 11, 20 I preferably provide apertures 29 and 30 in the side walls 13 and 14, respectively, of said bit carrying link 11. It will thus be evident that any coal particles which may be caught between the bit carrying link 11 and a tooth of the drive 25 sprocket may be readily released upon crushing thereof.

As best seen in Figs. 2 and 4 of the drawing, the aperture 30 is not of entirely uniform width, and it provides a ledge 31 which limits the down- 30 ward travel of the cutter bit 19 while preventing said cutter bit from closing said aperture 30.

In order to reinforce the lug 18 I also provide reinforcing bosses 32 which may be cast as an integral part of the bit carrying link 11. The bit carrying link 11 is also provided with aligned apertures 33 and 34 in the side walls 13 and 14 adjacent each end thereof, which apertures are adapted to co-operate with apertures 35, 36 of the same size on the connecting links 12. It will 40 be evident that a pair of apertures, such as apertures 33 of the bit carrying link, are adapted to align with an aperture, such as aperture 36 of the connecting link, and to receive a connecting pin, pintle or thimble 37 to attach said bit carrying links 11 and connecting links 12 for relative pivotal movement. It may be pointed out that the connecting links 12 carry bosses 38 spaced apart by a recess 39 providing an escape for material, which bosses 38 are adapted to bridge a pair of the 50 wings 25, 26 of the bit carrying links 11 and to co-operate with the bearing surfaces 27, 28 thereof to provide the "stiff back" construction of the cutter chain 10.

As seen in Fig. 5 of the drawing, the top portion 55 of each connecting link 12 may be rounded as illustrated at 39 to increase its strength, and the edges of the lower portion thereof may be chamfered or beveled, as illustrated at 40, to prevent any cutting action on the bit carrying links. It 60 may also be noted that the bottom of each connecting link 12 is arcuate, as seen at 41, whereby the said connecting links may readily travel around the rounded end of the cutter bar, in contact therewith. The connecting links 12 may also 65 be recessed at 42 to reduce the weight thereof and the amount of material employed.

Referring particularly to Figs. 6 and 7, it is to be noted that each pin 37 is of uniform outside diameter and is of hollow construction. It is 70 also provided with a pair of aligned radial slots or grooves 43 at each end thereof. The grooves 43 are preferably square. That is, their width and depth are of the same dimension.

As best seen in Fig. 7, the pin 37 has a length 75 substantially equal to the distance between the

outside surfaces of the side walls 13, 14. It may be mentioned that said outside surfaces of said side walls 13, 14 are relatively smooth whereby they may readily slide in the guideway of the cutter bar. By making the pin length substantially equal to the distance between the outside surfaces of the walls 13 and 14, a pin of maximum strength is provided, yet one which will not groove or cut the side walls of the cutter bar guideway.

It is also to be noted that the depth of the 10 grooves 43 is a dimension which is less than the thickness of the walls 13, 14. This insures that there will be a contact area between the pin 37 and the walls 13, 14, which is a complete cylinder. This provides for a maximum of sheer strength 15 for the pin 37.

The side walls 13 and 14 are provided with 20 grooves 44 which have a depth equal to the depths of the grooves 43 and which have a width which is also equal to the width of the grooves 43. This important relation has a number of functions 25 which will be evident from further description.

A retaining key 45 preferably made of soft iron and which has a dimension between diagonal corners substantially equal to the bore in the pin 37, is provided for extending through the bore of said pin 37 with its ends bent over, as illustrated at 46, 46, to prevent lateral movement 30 of the pin 37 relative to the bit carrying link 11 and to prevent relative rotary movement 35 therebetween.

The square key 45 preferably has a width and thickness substantially equal to the depth and width of the grooves 43 and 44. This insures 40 that there will be a tight fit between the bent over ends 46 of said key 45 and the grooves 43 and 44, whereby the key 45 will be held tightly in place without any movement whatever and will provide a very rigid attachment of the pin 37 and the bit carrying link 11. This prevents any undue wearing of the pin 37 and insures against the parts becoming loose and lost. Also, due to the fact that the square key 45 has a thickness equal to the depth of the grooves 43 and 44, the key 45 will have its outer surfaces substantially parallel 45 with the outer surfaces of the walls 13, 14 of the bit carrying links 11. This insures against the key 45 rubbing against the side walls of the cutter bar guideway and prevents grooving thereof or the wearing away of said key. Upon said pin 50 becoming worn due to the relative movement between the connecting link 12 and said pin 37, key 45 may be driven out by a punch, which will straighten out one bent over end 46. Pin 37 may 55 then be rotated 180 degrees to provide a new semi-cylindrical wearing surface, after which the straightened end 46 of said key 45 will be bent as illustrated in Fig. 7. It is also to be noted that grooves 44 do not extend completely through the side walls 13, 14 thus providing webs 48, 48 which 60 keep the bent ends 46 of keys 45 out of contact with the relatively movable connecting link 12. While the key 45 is preferably made of soft iron it may also be made of bronze, preferably silicon bronze.

It will be evident that the pin and key attaching means is a very simple construction, yet one which is very strong and may be readily assembled and disassembled in the field, with the use of only a few simple tools. For example, to remove the pin 37 it is only necessary to drive said pin out of the bit carrying link 11 by a few hammer blows, under which circumstances one bent over end 46 will assume an approximately upright position as shown in Fig. 8 and as illustrated in 75

dotted lines in Fig. 7. To fasten the pin 37 and lock it in place, the pin need only be inserted in the aligned apertures, such as 33, 36, after which the key 45, in the form illustrated in Fig. 8, may be inserted and the straight end 46 bent over and hammered into the grooves 43 and 44 as shown in Fig. 7. If desired both bent ends 46 may be hammered while in the grooves 44, thus expanding them to fit them very tightly in said grooves. 5
 10 Once in this position, the keys 47 are very tight as their four corners engage the interior of pins 37 and thus fit tightly. Bent over ends 46 also fit tightly in grooves 43 and 44. The bit carrying links 11, pins 37 and keys 45 are thus rigidly 15 attached together.

By referring to Fig. 7 it will be seen that the ends of the tubular pindle 37 are flush with the surfaces of the outer walls of the spaced apart plates 13, 14 of the bit carrying link. When the 20 parts are assembled as shown in Fig. 1, the interconnecting link 12 is pivotally connected to the bit carrying link 11 over a relatively large bearing surface afforded by the pindle 37 which extends through the aligned openings 33, 34 in 25 the side plates of the bit carrying link. The opening 35 in the interconnecting link 12 registers with the aligned openings 34 and fits closely between the inner walls of the side plates 13 and 14, as shown in Fig. 7, thereby affording a substantially adjustable pivotal connection between 30 the bit carrying link and each of the interconnecting links pivoted thereto. The extension of the pindle 37 through the openings in the side plates affords substantial resistance to shearing 35 over the relatively large circumference of the pindle 37 at the inner spaced-apart surfaces of the spaced-apart plates 13 and 14.

When the key or keeper 45 is to be placed in the locking position shown in Fig. 7, it has the shape 40 shown in full lines in Fig. 8. The right angle end portion 46 is square in cross-section, and is adapted to fit with its side walls in very close contact with the opposing side walls of the slots 43, 43 at opposite ends of the tubular pindle 37. The 45 end which projects through the tubular pindle 37 is then bent to the position shown in Fig. 7 so as to fit into the adjacent registering slots 43, 44, respectively located in the pindle 37 and the side plate 13, as shown in Fig. 7. It should be particularly understood that the right angle end portion of the key or keeper has a tight fit not only with the opposite walls of the slot 43 but also with the opposite walls of the slot 44 at both ends of the keeper.

55 The exposed flat surfaces of the right angle end portions 45 and 46 will then be in planes parallel to the planes of the outer surfaces of the side plates 13 and 14, and such exposed flat surfaces may be flush with the outer surfaces of the 60 side plates 13 and 14, as shown in Fig. 7.

The keeper when assembled as shown in Fig. 7 not only locks the pindle 37 against turning relatively to the bit carrying link and prevents the pindle from moving axially relatively to the bit 65 carrying link, but also cooperates with the pindle to rigidly connect the side plates 13 and 14 and securely hold them against movement toward or away from each other during feeding strains exerted on the various parts of the chain cutter during coal cutting operations. During operation of the chain cutter the interconnecting links move back and forth pivotally on the cylindrical bearing afforded by the pindle 37 and it is therefore important that the keeper shall secure the 70

pindle in fixed and rigid relation to the side plates of the bit carrying link.

When the bit holder carries the cutter bit in one of the outermost positions such as that shown in Fig. 4, the feeding movement of the chain cutter transversely of its path of travel tends to tilt the bit carrying link on the longitudinal axis of the chain. If the flanges 21, 22 were omitted, this tendency to tilt on the longitudinal axis of the chain would become more pronounced, and the stresses and strains tending to move the side plates 13, 14 out of parallelism would be greater than when the flanges 21, 22 are included. When the cutter bits are in their outermost positions and the tendency is to move the plates 13 and 14 toward each other, the openings in the side plates 13, 14 can be relied on to exert a clutching effect on the tubular pindle 37, so that the side plates 13, 14 will not bind on the interconnecting link 12. Any tendency to spread the plates 13, 14 by binding on the interconnecting link 12 will be resisted by the right angle portions 45, 46 of the keeper, as shown in Fig. 7.

The portion of the keeper between the right angle ends has its four edges fitted against the inner cylindrical wall of the opening extending through the pindle 37. Therefore when the keeper locks the tubular pindle in assembled relation to the bit carrying link, the side walls of the latter are rigidly connected at its end portions to afford the cylindrical bearings for the interconnecting links 12. Such reinforcement of the side plates of the bit carrying link enables the latter to more effectively resist the feeding stresses and strains which tend to tilt the chain on its longitudinal axis, and furthermore the close fitting relation of the parts illustrated in Fig. 7 distributes such tilting strains to adjacent bit carrying links, by reason of the stiffening of the chain relative to torsional strains.

While the pindle 37 has a sufficiently close fit in the assembly shown in Fig. 7, it is nevertheless removable by means of a manually operated punch applied to one end of the keeper or to one end of the pindle so as to secure bending of one of the right angle end portions of the keeper back toward its straight position shown in Fig. 8. After the chain has been taken apart and is to be reassembled, the same key or keeper that was withdrawn in the manner explained may be replaced, or if desired a new keeper may be used. It will be seen by referring to Fig. 1 that the right angle end portions 45, 45 of the keepers extend toward each other on opposite sides of the bit carrying link and that the exposed ends of the pindles 37 serve as portions of the lateral surfaces of the outer walls of the plates 13, 14 of the saddle type of bit carrying link. If the pindle 37 has become worn it may be reversed when replaced, by reason of the opposite slots 43. It should be particularly noted that the recesses 44, 44 in the side plates do not extend entirely across the latter. The bottoms of the recesses 44, 44 are integral extensions of the side plates 13, 14 so that the latter will be kept from spreading apart by the right angle end portions 45, 46 of the keeper.

70 This application is a division of my application for a Cutter chain, Serial No. 57,359, filed January 3, 1936.

Obviously those skilled in the art may make various changes in the details and arrangement of parts without departing from the spirit and scope of the invention as defined by the claims hereto appended, and I therefore wish not to be 75

restricted to the precise construction herein disclosed.

Having thus described and shown an embodiment of my invention, what I desire to secure by 5 Letters Patent of the United States is:

1. A bit carrying link for a mining machine cutter chain comprising a pair of parallel spaced walls, a bit carrying lug extending across the tops of said walls and connecting them together, a 10 pair of outwardly extending spaced apart flanges at each side of each link wall and adjacent the tops thereof, said flanges having bearing surfaces on their lower sides adapted to ride on a cutter bar.

15 2. A bit carrying link for a mining machine cutter chain comprising a pair of parallel spaced walls, a bit carrying lug extending across the tops of said walls and connecting them together, outwardly extending spaced apart flanges at each 20 end of said link, one adjacent each top corner thereof, said flanges having bearing surfaces on their lower sides adapted to ride on a cutter bar, spaced inwardly extending flanges at the ends of said side walls and adjacent the tops thereof 25 adapted to co-operate with connecting links to provide a stiff back chain.

3. A cutter chain for a mining machine comprising interconnected bit carrying links and connecting links, the bit carrying links comprising 30 spaced parallel side walls interconnected by a bit carrying lug extending across the tops thereof, the connecting links extending between said side walls, pins for connecting said links, each connecting link having an arcuate bottom surface, 35 spaced flanges extending outwardly from the side walls of said bit carrying links at the tops thereof, said flanges having bearing surfaces adapted to contact a cutter bar, outwardly extending gibs adjacent the bottoms of said bit carrying links, 40 said gibs having arcuate bottom surfaces, and means carried by said bit carrying lug for removably carrying a cutter bit.

4. A bit carrying link for a mining machine cutter chain comprising a pair of parallel spaced

walls, a bit carrying lug extending across the tops of said walls and connecting them together, longitudinally spaced outwardly extending flanges at each end of said link and adjacent the tops thereof, said flanges having bearing surfaces on their lower sides adapted to ride on a cutter bar, spaced inwardly extending means at the ends of said side walls and adjacent the tops thereof adapted to co-operate with connecting links to provide a stiff back chain, at least one of said side walls having an opening therein to permit escape of any trapped material. 5

10 5. A bit carrying link for a mining machine cutter chain comprising a pair of parallel spaced walls, a bit carrying lug extending across the tops of said walls and connecting them together, said lug having a bit carrying aperture the axis of which is at an angle to said walls, one of said side walls having an opening therein, a ledge in said opening above the bottom thereof and adapted 20 to support the bottom of a bit to prevent its closing said opening. 15

25 6. A bit carrying link for a mining machine cutter chain comprising a pair of parallel spaced walls, a bit carrying lug extending across the tops of said walls and connecting them together, inwardly extending bearing means spaced from said lugs, a pair of longitudinally spaced outwardly extending flanges adjacent the tops of each of said walls having cutter bar engaging bearing 30 surfaces, outwardly extending gibs on the bottoms of said walls, said gibs having arcuate bottom surfaces intermediate their ends. 35

40 7. A bit carrying link for a mining machine cutter chain comprising a pair of parallel spaced walls, a bit carrying lug extending across the tops of said walls and connecting them together, a pair of longitudinally spaced outwardly extending flanges adjacent the tops of each of said walls having cutter bar engaging bearing surfaces, outwardly extending gibs on the bottoms of said walls, said gibs having arcuate bottom surfaces intermediate their ends. 45

ROBERT K. JEFFREY.
